Attn:

UNITED STATES PATENT OFFICE.

RICHARD R. RICKETTS, OF SPRINGFIELD, MISSOURI.

DESIGN FOR A SEED-CASE.

No. 37,648.

Specification for Design.

Patented Nov. 7, 1905.

Application filed July 14, 1905. Serial No. 269,754. Term of patent 3½ years.

To all whom it may concern:

Be it known that I, RICHARD R. RICKETTS, a citizen of the United States, residing at Springfield, in the county of Greene, State of Missouri, have invented a new, original, and ornamental Design for Seed-Cases, of which the following is a specification, reference being had to the accompanying drawings, forming a part thereof.

In the drawings showing my new design,

Figure 1 is a front elevation, and Fig. 2 is an end elevation, thereof.

I claim—

The ornamental design for a seed-case, as shown.

RICHARD R. RICKETTS.

In presence of—

W. D. MURRAY,

J. F. RICKETTS.
